DESIGN FOR A SCALE INDICATOR

Lester D. Singleton, Rutland, Vt., assignor to
The Howe Scale Company, a corporation of
Vermont

Application June 3, 1946, Serial No. 130,358

Term of patent 14 years

(Cl. D52—10)

To all whom it may concern:

Be it known that I, Lester D. Singleton, a citizen of the United States and a resident of Rutland, in the county of Rutland and State of Vermont, have invented a new, original, and ornamental Design for a Scale Indicator, of which the following is a specification, reference being had to the accompanying drawings, forming part thereof and in which

Fig. 1 is a front elevational view of a scale indicator showing my new design,

Fig. 2 is a side edge view of said design.

I claim:

The ornamental design for a scale indicator, substantially as shown.

LESTER D. SINGLETON.
